UNITED STATES PATENT OFFICE.

ADOLPH C. MENNINGEN, OF MILWAUKEE, WISCONSIN, ASSIGNOR TO KOEHRING COMPANY, OF MILWAUKEE, WISCONSIN, A CORPORATION.

AUTOMATIC POWER-DISCHARGE CHUTE.

Application filed February 5, 1926. Serial No. 36,200.

In the construction of concrete mixing machines today, particularly those of larger capacities, the discharge means for the mixer requires the employment of considerable power for the operation thereof. The said discharge means is therefore commonly actuated by connecting the same up with the power plant of the mixer to be driven therefrom. The connecting up has usually been established heretofore by the use of more or less complicated clutch mechanism under manual control, and requiring the throwing in of the clutch to turn the discharge chute to discharging position, the throwing out of such clutch to enable the said chute to remain in discharge position, and the throwing in again of the said clutch to return the chute to non-discharging position.

An essential object of the present invention has been to dispense with the use of clutch mechanism of the type above referred to, and utilize a special stopping and starting mechanism of quite a different nature for throwing into action the chute moving means, one more simple, very effective, and eliminating the disadvantages that are usually incident to the employment of clutch parts of either the jaw or friction classes.

An additional object of the present invention is to improve generally a stopping and starting mechanism of the class above characterized such as embodied in the pending application of Webb, Serial No. 5827, filed January 30, 1925, in which are used certain worm gear actuating and controlling parts, the efficiency of which by the improvements hereof has been materially increased.

A full understanding of the invention will be had on reference to the following description, in conjunction with the accompanying drawings in which:

Figure 1 is a fragmentary view in elevation showing a portion of a concrete mixer with the mixing drum broken away to illustrate its discharge chute which is connected up with the stopping and starting mechanism of this invention under the control of a batchmeter, so known in the art; a portion of a loading skip being also shown in its cooperative relation with the batchmeter.

Figure 2 is a view of substantially all the parts shown in Fig. 1 looking at a right angle to the view of Fig. 1, and showing the safety coupling or connection between the

discharge chute shaft and the starting and stopping mechanism, partly broken away and shown in section.

Figure 3 is a sectional view of the casing of the stopping and starting mechanism 60 showing the cam more clearly and certain driving connections for transmitting movement from the power actuating means to the chute, the view being taken on about the line of 3—3 of Fig. 4. 65

Figure 4 is a horizontal sectional view showing more clearly certain parts seen in Fig. 3.

Figure 5 is a vertical section taken on the planes indicated approximately by lines 70 5—5 of Fig. 3.

Figure 6 is a sectional view taken through the aligned control shafts at the bottom of the casing which contains the starting and stopping parts and driving connections. 75

Figure 6^A is a sectional view showing the relation of the starting lever and its release lever to the driving shaft and co-operative features there-between, dotted lines showing the range of movement of the lever and co-action between them and the driving pins. 80

Figure 7 is a sectional view taken about on the line 7—7 of Fig. 6^A.

Figure 8 is a detailed view showing a little more clearly the co-operation of the 85 roller carried by the starting lever, with one of the driving pins.

Figure 9 is a sectional view taken on the line of 9—9 of Fig. 8, and fragmentary.

Figure 10 is a fragmentary view, partly in 90 section, showing slightly modified construction of the starting lever and its arm.

Figure 11 is a view illustrating how the mechanism of the invention may be inverted and arranged on the frame work of the machine so that it is supported by a bottom bracket instead of being suspended from a top bracket supporting means, the construction operating on the same principle as that shown in the previously described figures 95 100 above mentioned.

Referring first to Figs. 1 and 2, 1, designates the mixing drum of any conventional type of mixing machine; 2, the fragmentary portion of a loading skip; 3, a batchmeter of the construction substantially as shown and described in the U. S. Letters Patent of Winkler No. 1,451,483, issued April 10, 1923; and 4, associated starting and stopping mechanism with driving parts controlled 105 110 115

thereby to transmit movement from the drum 1, or any suitable source of power or movement, to the discharge chute 5.

The chute 5 is a reversible chute and at Fig. 1 it is shown in a full line position in which it is adjusted to discharge the contents of the drum 1. It may be shifted to reverse its inclination in which event it will have assumed a non-discharging position in which it may or may not act as a mixing element as may be required or desired in service. For the purposes of this specification the chute 5 is shiftable from a non-discharging to a discharging position and the means for doing this work will now be set forth.

Enmeshed with the teeth of the gear ring 6 of the drum 1 is a spur gear 7, which is constantly driven thereby so long as the drum 1 is in motion. The drum 1 is driven from the power plant of the mixer in the well known manner. The gear 7 is carried by a driving shaft 8 used to transmit motion from the drum 1 to the chute 5. The shaft 8 enters the casing 4 and is equipped inside the casing with a driving worm 9. The worm 9 has its spiral portion engaging permanently with the worm teeth 10' of a worm gear 10 which is constantly driven or rotated thereby, being loosely mounted upon a shaft 11. Coaxial with the worm gear 10 is a second worm gear 12, whose worm teeth 12' are symmetrical with those of the gear 10, the said teeth of the gear 12, however, being interrupted or omitted as shown at 12^a in Fig. 4 and in Fig. 6^a. The gear 12 is keyed to the shaft 11, as shown at 13 (see Fig. 7) and the interrupted portions of the teeth of the gear 12, which for convenience will be called recesses 12^a, are of such a length that the worm 9 may turn freely in the space between the terminals of said recesses 12^a, and the gear 12 under such conditions will remain inactive. The gears 10 and 12 might be said to be a composite gear, considered collectively, one of the parts recessed at diametrically opposite portions of its periphery, as at 12^a, so that it may remain unaffected by the drive of the other part, or so that the worm 9 will not actuate the gear or gear part 12 when disposed in and opposite either one of the recesses 12^a. For the purposes hereof, however, we shall consider the gears 10 and 12 as separate gears because they may function together or separately, their teeth, however, being adapted to line up with one another so that they may act substantially as a single gear when both are simultaneously engaged by the worm 9.

The gear 12 being keyed to the shaft 11 will drive the shaft 11 when said worm 12 is driven. The shaft 11 extends through the sides of the casing 4 and is suitably journaled therein, and equipped at one outer end

with crank arm 14 connected by a link 15 with an arm 16 which is carried rigidly by the chute shaft 17. The chute shaft 17 is suitably connected by an arm 18 and linkage 19 to the chute 5 (see Fig. 1). If the arm 14 swings through an arc of approximately 180° then arm 16 will reverse the inclination of the chute 5 from the position of Fig. 1 and adjust it to a non-discharging position. A second movement of the arm 14 of about 180° will raise the arm 16 to its original position, as shown in Fig. 1 in full lines and move the chute 5 to a discharging position again.

It will, therefore, be understood that for practical purposes the worm gear 10 is a driving worm gear and the worm gear 12 is a driven worm gear, and when the two gears are connected together motion will be transmitted from the drum 1 to the chute.

The means for controlling the connection of the parts 10 and 12, and their disconnection will now be set forth.

The batchmeter 3 being of a known type is not described in detail as it suffices to state that it is operated from the loading skip 2 as said skip reaches a position about as shown in Fig. 1 wherein a trip rod 18^a is shown in the act of being struck by an abutment 19^a on the skip 2. The abutment in this way operates the rod 18^a to swing the arm 20 of the batchmeter and set the batchmeter into operation to predetermine and control the mixing period of the drum 1 after the known manner. This mixing period is usually a minute or a minute and a half and upon its expiration the mechanism within the batchmeter causes its control arm 21 to move up, lifting on the lift rod 22 and raising the actuating arm 23 on the outside of the casing 4. The arm 23 is carried by the shaft 24 which is a short shaft mounted in a bearing at one side of the casing 4 and having rigidly attached to its inner end a fork or rocker arm 25. The fork of arm 25 is preferably provided by the use of two parallel bars, as seen in Figs. 3, 4, 5 and 6, one of which bars is locked to shaft 24 (as by the use of a bolt as seen in Fig. 6), and the other of which bars is pivoted on a shaft 28 hereafter to be described, and the two bars being rigidly fixed together, as by being formed integral through an integrally cast connecting cross web 25^a, as seen in Fig. 5. This rocker arm 25 has pivoted therefrom between the bars of the fork a locking pawl 26, which serves as a positive lock for the whole discharge mechanism after the batchmeter 3 has been set, and during the period of its controlling operation, at which time the chute 5 is in non-discharging position.

The locking pawl 26 is provided with a notch or locking recess which is arranged to engage the tail of a release lever 27, the

said release lever being normally held in such engagement by means of a coiled spring 28^a. The pivotal connection of the pawl 26 with the rocker arm or fork 25 consists of 5 a pin 29^a.

The release lever 27 is mounted upon a short shaft 28, somewhat similar to, and in alignment with the shaft 24. The said shaft 28 is supported by a bearing in the side 10 of the casing 4 opposite that which supports the shaft 24. The shaft 28 in addition to carrying the release lever 27 at its inner end, carries at its outer end a manual control handle 29, peculiarly attached thereto, 15 so as to have an abrupt abutting engagement at 29^a with a collar 30 pinned to the outer end of the shaft 28. Also, handle 29 has a camming engagement at 29^b with the collar 30 and between the collar and the 20 adjacent side of the casing 4.

The release lever 27 carries a roller 31 adapted to engage the lower end of a starting lever 32, which may be described as a 3-armed lever. At its upper end the starting lever is connected by a coiled spring 33^a with a suitable portion of the casing 4 and said spring 33^a tends to move the lever 32 toward the shaft or axis 11. The release lever 27, however, is a detent and normally 25 tends to hold the starting lever 32 in a position at its limit of movement away from the shaft 11 with the spring 33^a expanded and under tension.

The starting lever 32 functions peculiarly 30 as a means to connect the constantly moving driving worm 10 with the intermittently operable worm 12. For this purpose, see Fig. 6^a, the lever 32 is provided on its long upper arm with an abutment cam 33, seen 35 best in Fig. 7, the inclined portion of this cam being adapted to engage an inclined head 34 on each one of two driving pins 35 which are yieldingly mounted on the worm gear 12 at opposite sides of the axis of the latter, that is to say at opposite sides of shaft 11. The pins 35 have shoulders 36 engaged 40 by ends of springs 37 locked in recesses in the body of the worm 12, said springs 37 engaging the inner ends of the said recesses and normally tending to project the pins 35 45 outwards or in a direction away from the driving worm gear 10.

The driving worm gear 10 is provided 50 with a series of, preferably about seven, openings 38, see Fig. 8, which openings are adapted to register with the pins 35 and receive the inner ends of said pins at certain times when the pins are projected at such inner ends from their recesses, under 55 the action of the cam 33. In other words, one of the functions of the starting lever 32, is, when released, to carry its cam abutment 33 against the head 34 of a pin 35 and project said pin at its inner end into 60 engagement with one of the openings 38

when said opening comes opposite or registers with the pin. Under these conditions the operated pin 35 will connect the driving worm gear 10 with the driven worm gear 12 and then the worm gear 12 will be moved 70 a short distance by the pin 35 until its teeth at the left end of the uppermost recess 12^a, seen in Figs. 3 and 4, become engaged with the spiral of the driving worm 9. At such time the spiral or thread of the driving worm 9 by contact with the teeth of the driven worm gear 12 takes the load of the drive of said worm gear 12, which has previously been carried by the interlocked pin 35, and under these conditions, since the 80 worm 9 engages both of the worm gears 10 and 12, the frictional driving stress on the pin 35 being relieved, its respective spring 37 will act to return the pin to a position in which it is released from engagement 85 with the worm gear 10.

Of course, the pins 35 work in alternation, the particular pin being projected when the release lever 27 becomes disengaged from the starting lever 32 as previously suggested, so that the spring 33^a may act as a motor to carry the lever 32 toward the shaft 11. When once the worm gear 12 has been placed in proper engagement with the driving worm 9, the latter will turn the worm 95 gear 12, its shaft 11 and arm 14 approximately a half revolution, all initiated by the batchmeter operation of lifting the rocker arm 25 on upward movement of the arm 23 by the lift rod 22. Such half 100 revolution will turn the discharge chute from a non-discharging position to a discharging position in which it is shown in full lines in Fig. 1. Of course, as soon as the gear 12 has made a half revolution, its 105 recess 12^a which was previously lowermost, see Fig. 3, arrives at its uppermost position and causes a disengagement of the driving worm 9 from active operating relation to said gear 12. The starting lever 32 is 110 restored to its position under the control of the detent or release lever 27, by engagement of the shank of the pin 35, opposite the pin 35 acted upon by the cam part 33, in a starting operation. The said second pin with its 115 shank, of course, turns with the gear 12 after said gear commences to move through its connection with the gear 10, or worm 9, so that when said second pin reaches a point opposite a roller 40, carried by the lever 32, 120 the lever 32 will be forced to the left at its upper end bringing its lower end into engagement with the detent or release lever 27, which holds it in the full alined position of Fig. 6^a, a restored position, again placing 125 the spring 33^a under tension.

The roller 40 is rather peculiarly mounted on the lever 32 being carried by a small pivoted arm 41, which has a slight rocking movement. In addition to its function, as 130

above described, of restoring the lever 32 to its position engaged by the part 27, the roller 40 acts as the stop to hold the gear 12 with its upper recess 12^a arranged so that the worm 9 is centrally disposed in the recess properly disengaged from the gear 12 until the latter is propelled into such an engagement at a certain time by the cam part 33.

The lever 32, in addition to its upper arm 10 and its lower arm, has a middle lateral arm 42 provided with a cam or inclined extremity 43 that functions in a special manner. The said cam 43, when the lever 32 is in full-line position of Fig. 6^a, is adapted to engage either of the locking pins 35, as the gear 12 turns in a clockwise direction (see Fig. 9). Thus, if the spring 37 of one of the locking pins 35 should become broken, or such pin not restored through lack of lubrication, or for some other cause, it will be positively disengaged from the driving worm gear 10 by the arm 42 and its cam 43. The co-operation of the part 42 with the pin 35 relative to which it is actively engaged performs a stopping function, moreover, to insure the stopping of the worm gear 12 in a centralized position, as regards the relation of the worm 9 and the uppermost recess 12^a. It is, at this time, of course, that the drive from the worm 9 to the gear 12 is discontinued, as when the chute 5 has reached a non-discharging position or discharging position, as the case may be.

The heads 34 of the pins 35 are each formed with an inwardly facing arcuate notch snugly contacting with and conforming to the contour of the periphery of a disk-like part 44, which is formed integrally with a hub extension 45 of the driven gear 12. The purpose of this contact is to maintain pins 35 from having independent angular movement, so that the cam surfaces of the heads 34 of said pins 35 are retained always in proper position to be engaged by the co-operative cam 33.

The release or detent lever 27, being carried by the shaft 28 on which the handle 29 is mounted, may be tripped at any time by hand, except when the batchmeter 3 has been set by the trip rod 18^a, and while the chute 5 is in its non-discharging position. It will be obvious that it is not desired that the starting lever 32 be susceptible of being released when the mixing period is being controlled by the batchmeter 3. If this were possible, then the control of the mixing operation by the batchmeter might be interfered with. For this reason, the locking pawl 26 is engaged with the release lever 27 when the starting devices are under the control of the batchmeter and premature ending of the mixing period is prevented.

By reference to Figs. 3 and 7 it will be seen that the hub extension 45 of the worm gear 12, in addition to having the round disk

part 44, is provided with a cam 46, the cam surface of which is adapted to contact with the locking pawl 26, when the chute 5 has been moved to discharge position by operation of the worm gear 12. Under such conditions, the cam 46 maintains contact with the pawl 26 and holds it out of engagement respecting the detent or release lever 27. Therefore, it is possible at this time, namely, when the pawl 26 is so disengaged, for the operator to turn the handle 29 loose on the shaft 28, thereby to trip the release lever 27 out of engagement respecting the starting lever 32, to cause said starting lever to perform its starting function and return the chute 5 to a non-discharging position at the will of the operator. This action of the handle 29 involves engagement between the handle abutment 29^a and the fixed collar 30 of the shaft 28. If the handle is turned in an opposite direction the cam portion 29^b of the handle will go into action and cause a clamping or binding action between the release lever 27, rocker arm 25 and the side of the casing 4 in such a manner as to hold those of these parts which are movable, against operation. This is only done when the operator of the machine wishes to prevent the chute 5 from being turned to the discharging position under the influence of the tripping action of the batch-meter 3 through its lift rod 22. There are occasions when it is possible that the discharging of the drum 1 of the mixer should be delayed beyond the mixing period prescribed by the batchmeter, hence the control last described which may be exercised by the manual lever 29. Therefore, while the handle or lever 29 cannot be used to anticipate the termination of the mixing period, or in other words, cause a discharge of the drum before the batchmeter control period is over, it may be used to prolong the time that the batch of concrete is retained in the drum, something which could do no harm. A safety coupling means is shown intermediate of the chute operating shaft 17 and the arm 16 attached to the rod 15, but as this safety coupling is described in the Webb application, previously referred to, and forms no part of the present invention, it is not treated in detail herein.

It is notable from Fig. 6^a that when the starting lever 32 is released, it rocks in such a manner that its arm 42 moves downward out of the path of the lowermost locking pin 35.

Concise describing the complete operation of my mechanism, it is noted that the parts, as in the normal positions of Fig. 3, are ready to be operated by the batchmeter 3 to cause a movement of the discharge chute to discharging position. The worm 9 is in constant motion, as is the gear 10. The gear 12 is stationary. At the end of the mixing

period the batchmeter 3 by upward movement of its arm 21 raises the rocker arm 25 and through the part 26 actuates the detent lever 27 to release the starting lever 32. The 5 spring 33^a now pulls the starting lever 32 to the right and causes it to act through its cam 33 to interlock the gear 12 manually with the gear 10, and sufficiently long so that the two gears rotate together in order to accurately mesh the gear 12 with the worm 9. The interlock between the two gears 10 and 12 is now removed by retraction of the operative locking pin 35 and the gear 12 rotates a half revolution until its previously lower 15 recess 12^a is uppermost. The chute 5 by the action of the gear 12 is moved to discharge position, as shown in Fig. 1. The cam 46 now engages the pawl 26 and holds it away from the release lever 27. The operation of 20 the chute may now be controlled by the operator, who may actuate the lever 27 at any time to cause operation of the starting lever 32 to effect retraction of the chute 5 to normal non-discharging position. When chute 25 5 is back at normal position, the cam 46 is inactive relative to the pawl 26 and the mechanism is again under the control of the batchmeter and cannot be controlled manually to cause operation of the chute.

30 But while the parts are in the full line positions of Fig. 3, should the operator not wish to permit discharge action of the chute 5, he may prevent the batchmeter 3 from initiating the action of the starting lever 32, 35 by turning the handle 29 to render the cam 29^b effective and prevent a rocking of the lever 27 to release the lever 32. Under these conditions, the batchmeter arm 21 moves upwards, but does not effect operation of the 40 arm 25, though power is stored up in the batchmeter spring (not shown) which acts on the arm 21 to cause said arm 21 to move the arm 25 just as soon as the operator turns the handle 29 to release his control by which 45 he delays the turning of the chute 5 to discharge position.

The arm 42 and the lever 32, shown as an integral unit, may be in two parts as shown in the modified view in Fig. 10 as 42' and 32' 50 respectively. This arrangement may be used as a further assurance for gaining a positive locking together of the worm wheels 10 and 12 by means of the pins 35. The independent arm 42' shoulders against the 55 shank of the pins 35 during the period in which the lever 32' is moving to the right, until a lug on the lever 32' contacts with the upstanding leg *b* of the arm 42', from which moment the abutment *a* rocks downwardly to 60 allow the pin 35 to pass by with the rotation of the member in which the said pins are housed. The difference between the two arrangements is a change in the movement time of the arm 42', which is later than that 65 of the arm 42 and this insures a complete in-

sertion of the pin under the cam 33^a and a positive locking of the elements 10 and 12 before the latter (12) is permitted to revolve, by virtue of the detention offered by the arm 42' being removed. The arm 42' is given 70 the necessary tension by attaching a spring *d* that may be suitably anchored to a convenient point of the casing 4.

On reference to Figure 11 it will be observed that the casing illustrated in Figures 75 1 to 3 inclusive, with its enclosed mechanism, is rearranged slightly, being mounted upon the frame work of the machine with an arrangement inverted as compared with that hereinbefore described. This view simply 80 illustrates that it is not desired to be limited to any particular arrangement of the starting mechanism because such phase of the presentation of the invention is not material so long as the said mechanism is suitably 85 connected up with the chute to operate it, and is likewise connected up with the batch meter to be controlled thereby.

Having thus described my invention, what I claim as new and desire to secure by Letters Patent of the United States, is:—

1. In a chute operating mechanism, in combination, a batch meter, a chute, means for operating said chute comprising a constantly operated driving gear, a second gear 95 operably connected with the chute, and batch meter controlled means to interlock the second gear with the first mentioned gear for starting the movement of the two gears together.

2. In a chute operating mechanism, in combination, a power driving member, a power driven member, a chute operably connected with the power driven member, a batch meter, means to interlock the power 105 driving member with the power driven member, and means connecting the last mentioned means with the batch meter for control thereby.

3. In a chute operating mechanism, in combination, a power driving member, a power driven member, a chute operably connected with the power driven member, a batch meter, means to interlock the power driving member with the power driven member, and means connecting the last mentioned means with the batch meter for control thereby, and a driving part for the power driving member adapted to drive the driven member after the movement of the latter has been initiated by the operation of the means interlocking the same with the power driving member.

4. In a chute operating mechanism, in combination, a power driving member, a power driven member, a chute operably connected with the power driven member, a batch meter, means to interlock the power driving member with the power driven member, and means connecting the last mentioned 125 130

means with the batch meter for control thereby, and a driving part for the power driving member adapted to drive the driven member after the movement of the latter 5 has been initiated by the operation of the means interlocking the same with the power driving member, and means for rendering the interlocking means inactive after the power driven member has been placed in co- 10 operation with the driving part for actuation thereby.

5. In chute operating means, in combination, a batch meter, a chute, a driving gear, a driving part normally operating said gear, 15 a driven gear adapted to be operated by said driving part but normally out of connection therewith, means for interconnecting the driven gear with the driving gear so as to bring the driven gear into operative connection 20 with the driving part, and actuating means controlled by the batch meter for operating the last mentioned means.

6. In chute operating means, in combination, a batch meter, a chute, a driving gear 25 a driving part normally operating said gear, a driven gear adapted to be operated by said driving part but normally out of connection therewith, means for interconnecting the driven gear with the driving gear so as to 30 bring the driven gear into operative connection with the driving part, and actuating means controlled by the batch meter for operating the last mentioned means, and means for rendering the interconnecting means be- 35 tween the gears inactive when the driven gear has been connected up with the driving part.

7. In combination, a chute, two coaxially mounted driving and driven worm gears, a 40 worm normally driving the driving worm gear and meshing therewith, the driven worm gear having a recess in its periphery to receive the worm to prevent operation thereby, both of the worm gears having 45 teeth, teeth of one forming continuations of the teeth of the other, starting mechanism including means for connecting the driven worm gear with the driving worm gear to bring the teeth of the driven worm gear into 50 engagement with the driving worm, means to disconnect the driving and driven worm gears when the driven worm gear has been interengaged with the driving worm, and means connecting the driven worm gear to 55 operate the chute.

8. In combination, a chute, two coaxially mounted driving and driven worm gears, a worm normally driving the driving worm gear and meshing therewith, the driven 60 worm gear having a recess in its periphery to receive the worm to prevent operation thereby, both of the worm gears having teeth, teeth of one forming continuations of the teeth of the other, starting mechanism

including means for connecting the driven 65 worm gear with the driving worm gear to bring the teeth of the driven worm gear into engagement with the driving worm, means to disconnect the driving and driven worm gears when the driven worm gear has been 70 interengaged with driving worm, and means connecting the driven worm gear to operate the chute, and a batch meter for causing actuation of the starting mechanism aforesaid. 75

9. In combination, a chute, two coaxially mounted driving and driven worm gears, a worm normally driving the driving worm gear and meshing therewith, the driven worm gear having a recess in its periphery to receive the worm to prevent operation 80 thereby, both of the worm gears having teeth, teeth of one forming continuations of the teeth of the other, starting mechanism including means for connecting the driven worm gear with the driving worm gear to bring the teeth of the driven worm gear into 85 engagement with the driving worm, means to disconnect the driving and driven worm gears when the driven worm gear has been interengaged with the driving worm, and means connecting the driven worm gear to operate the chute, power means for putting the starting mechanism aforesaid into action, 90 other and manual means for causing the operation of said starting mechanism and means for preventing for a certain lapsed time the operation of the starting mechanism by said power means. 95

10. In combination, a chute, two coaxially mounted driving and driven worm gears, a worm normally driving the driving worm gear and meshing therewith, the driven worm gear having a recess in its periphery to receive the worm to prevent operation 100 thereby, both of the worm gears having teeth, teeth of one forming continuations of the teeth of the other, starting mechanism including means for connecting the driven worm gear with the driving worm gear to bring the teeth of the driven worm gear into engagement with the driving worm, means to discontinue the driving and driven worm gears when the driven worm gear has been 105 interengaged with the driving worm, and means connecting the driven worm gear to operate the chute, batch meter controlling means for causing operation of the starting mechanism, manual means also for causing operation of the starting mechanism and means cooperative with said manual means for interfering with the operation of the starting mechanism by the batch meter controlling means. 110

11. In combination, a chute, two coaxially mounted driving and driven worm gears, a worm normally driving the driving worm gear and meshing therewith, the driven 115

- worm gear having a recess in its periphery to receive the worm to prevent operation thereby, both of the worm gears having teeth, teeth of one forming continuations of 5 the teeth of the other, starting mechanism including means for connecting the driven worm gear with the driving worm gear to bring the teeth of the driven worm gear into engagement with the driving worm, means 10 to discontinue the driving and driven worm gears when the driven worm gear has been interengaged with the driving worm, and means connecting the driven worm gear to operate the chute, batch meter controlling 15 means for causing operation of the starting mechanism, manual means also for causing operation of the starting mechanism and means cooperative with said manual means for interfering with the operation of the 20 starting mechanism by the batch meter controlling means, and means operated by the driven worm gear for preventing said interfering means from being operated when the chute is in a certain position.
- 25 12. In a chute operating mechanism, in combination, a chute, an operating device for said chute including power driven instrumentalities, a connection between said chute and said power instrumentalities, a 30 batch meter for causing operation of the chute by the power driven instrumentalities, other means for causing operation of the chute by the power driven instrumentalities, and means for rendering the last mentioned 35 means inoperative when the chute is in a certain position.
13. In a chute operating device, in combination, power driven instrumentalities, a chute, means to operate the chute from the 40 power instrumentalities, a batch meter to control the operation of the last named means, the chute being movement from a non-discharging to a discharging position, manual means to cause operation of the 45 chute by the power instrumentalities, and means to prevent operation of the chute under the control of the manual means when the chute is in non-discharging position.
14. In a chute operating device, in combination, power driven instrumentalities, a chute, means to operate the chute from the power instrumentalities, a batch meter to control the operation of the last named means, the chute being movement from a 55 non-discharging to a discharging position, manual means to cause operation of the chute by the power instrumentalities, and means to prevent operation of the chute under the control of the manual means when 60 the chute is in non-discharging position, and means controlled by said manual means for delaying the operation of the chute incident

to the operation of the power instrumentalities under the control of the batch meter.

15. In a chute operating device, in combination, a chute, means to actuate the chute including a worm gear adapted to be engaged and actuated by said worm but having a recess to receive the worm and thus prevent such engagement, means for centering the worm gear so that the worm is 65 fully out of operative engagement with the worm gear and centered with respect for said recess, means for shifting the worm gear to engage it with the worm. 70

16. In a chute operating device, in combination, a chute, means to actuate the chute including a worm gear adapted to be engaged and actuated by said worm but having a recess to receive the worm and thus 80 prevent such engagement, means for centering the worm gear so that the worm is fully out of operative engagement with the worm gear and centered with respect for said recess, means for shifting the worm gear to engage it with the worm, the centering means cooperating to limit movement of the worm gear in either of opposite directions. 85

17. In combination, a rotative concrete mixing drum, a discharge device therefor, batchmeter control means for causing the application of power to the discharge device for setting it in an operative position, and means for simultaneously discontinuing the 90 said application of power to the discharge device and stopping the same after it has reached the desired operative position, the power applying means comprising instrumentalities for connecting the drum with the 95 discharge device to actuate the latter. 100

18. In combination, a rotary mixing drum, a discharge device therefor, batchmeter control means to connect the discharge device with the drum for actuation thereby, manual 105 means to interfere with the operation of the batchmeter control means and delay the action of the latter, and means adapted to be operated by a loading skip for restoring the discharge device after it has been operated 110 by the drum as aforesaid.

19. In combination, a rotary concrete mixing drum, a discharge chute therefor, batchmeter control means for actuating said discharge chute including connections intermediate the drum and the chute for transmitting motion of the drum to the latter, and means adapted to be operated by a loading skip for actuating the discharge chute to cause it to assume a non-discharging position 115 120 in relation to the drum.

In testimony whereof I affix my signature.

ADOLPH C. MENNINGEN.
